SCREENING APPARATUS

Hugh E. Brown, Cleveland Heights, and Stewart Grant, Cleveland, Ohio, assignors to The W. S. Tyler Company, Cleveland, Ohio, a corporation of Ohio

Application April 1, 1936, Serial No. 72,076

2 Claims. (Cl. 209—347)

The present invention, relating as indicated to screening apparatus, is directed more particularly to apparatus for the screening of bulk materials. The principal object of the invention is the provision of a screening apparatus in which the weight of the screen and the load passing thereover do not rest upon, and therefore do not affect, the vibrating means and the freedom of movement thereof. Other objects of the invention are the provision of a screening apparatus and means for electro-magnetically vibrating the same in which the vibrating means may be initially designed and adjusted during manufacture to the particular screen without the necessity for subsequent adjustment in the field. Other objects of the invention will appear hereinafter.

To the accomplishment of the foregoing and related ends, said invention, then, consists of the means hereinafter fully described and particularly pointed out in the claims; the annexed drawing and the following description setting forth in detail certain means of carrying out the invention, such disclosed means illustrating, however, but one of the various ways in which the principle of the invention may be used.

In said annexed drawing:

Fig. 1 is a side elevation of our improved screening apparatus mounted in an inclined position;

Fig. 2 is an enlarged side elevation of the frame, screen and vibrating mechanism therefor;

Fig. 3 is an end elevation partially in section showing the resilient means for mounting the movable screen-carrying frame; and Fig. 4 is a partial transverse section showing a two-deck screen.

Fig. 5 is an enlarged portion of Fig. 2 showing the electro-magnetic vibrating structure in detail.

In the screening of coarse material it has always been found extremely difficult to secure continuous and effective action and to construct a machine capable of screening various sizes of material and varying loads of material even though adjustments were incorporated in the machine which made it possible to vary the intensity and amplitude of movement imparted to the screen in order to accommodate this movement to the material. This has been true of all types of screening apparatus operated on coarse materials, but has been particularly true of electro-magnetically operated screening apparatus, in which either the screen or screen-carrying frame was vibrated at an angle to the plane of material passing thereover by electro-magnetic means. In

this latter construction the load of material on the screen necessarily changed the gap between the armature and the field of the electro-magnetic means and this required constant adjustments which were secured by resilient means incorporated in the electro-magnetic means. The adjustment of the resilient means to cause greater or less tension between the armature and field was difficult to make accurately, and in practice was not always successful in securing either accuracy of separation or high capacity for the apparatus.

We have developed an electro-magnetically operated screening apparatus in which the electro-magnetic means are independent of the mounting for the screen-carrying frame and are not affected by the load on the screen-carrying frame. In this way we have found that it is possible to initially proportion the electro-magnetic apparatus to the screen and screen frame and the mounting therefor, adjust or set these during manufacture, and thereby render the apparatus continuously proportioned and adjusted to secure the action required regardless of the size or weight of material passing over the screen.

Referring now to Fig. 1 of the drawing, our improved screening apparatus consists of a frame or base 1 mounted in an inclined position upon supports 2 and 3, which in turn may either be supported from overhead or mounted upon the floor 4. Resiliently mounted upon the fixed frame 1 is a movable frame adapted to carry the screen cloth, as will presently be explained, which consists of spaced parallel angular members 10 provided with exteriorly extending plates or brackets 11 and secured together by means of transverse members 12. The exteriorly extending brackets 11 on the screen-carrying frame 10 are mounted between coil springs 13 and 14, a pair of which are disposed adjacent either end of the screen-carrying frame, the lower springs being in turn mounted upon the rigid frame 1 and the upper springs being mounted between the brackets 11 and an adjustable washer 14', the position of which may be adjusted and fixed by means of a nut 15 engaged upon a stud 16 extending from the rigid frame through the centers of the coil springs and above the same.

The screen-carrying frame 10 may be provided with one or more decks or screens which may be removably secured therein in various ways. As here shown, the frame is provided with two screens 20 and 21 arranged in spaced parallel relation, each screen being provided with a bent or curled edge portion 22 engaged by a flanged edge 55

of a clamping member 23, which is secured in the position shown in Fig. 4 by means of a threaded stud 24 and cap screw 25 mounted on the outside of the frame for convenient adjustment. It will be seen from the description up to this point that our apparatus includes a rigid sub-frame and a freely, resiliently mounted screen-carrying frame supported thereon by means of opposing springs which place the screen-carrying frame in condition for free floating movement in a plane at right angles to the plane of the rigid frame.

The screen-carrying frame 10 is vibrated by an electro-magnetic device consisting of a coil 30 fixed to the side of the frame 10 and a floating armature 31 in the form of a plate with ends projecting beyond the coil 30, where they are mounted between opposed pairs of springs 32. A pair of cooperative striking blocks are mounted on either side of the field, one block 33 being secured to the frame and the other block 34 being secured to the armature. We employ preferably four electro-magnetic devices, mounting two on either side of the frame, each being approximately one-fifth or one-fourth of the total length of the screen frame away from the end thereof, and have found that these positions give the best effect for the electro-magnets, as the elastic deflections of screen and frame will have the least effect in lessening the amplitude of motion of all parts of the screen surface if the electro-magnets are mounted as stated. The best screening effect is secured when the screen is accelerated downward away from its load so that the screen and load part company on the downward motion of the screen, as this allows the screen to clear itself, jolting out any pieces of material which have stuck in the mesh of the screen and allowing all of the material on the screen to shift its position before again being contacted by the screen on the upward movement of the latter. It is also desirable in securing the best results to provide rapid upward acceleration of the screen and, to some extent, it is immaterial whether the electro-magnetic devices employed operate to pull the screen away from the material or to push the screen up against the material, provided that these same means or other means provide a similarly rapid return movement. In our apparatus the armature is pulled downward toward the electro-magnet, in turn accelerating the screen downward. The armature is then returned by means of the pairs of springs 32. The frequency, and amplitude and the form of the motion given to the screen depend upon the frequency and type of current supply to the electro-magnet, the stiffness of the springs effecting the return movement of the armature and the armature weight. The action of the screen will depend upon the factors named above and upon the proper proportions of the weight of the armature, the vibrator springs and the pull of the electro-magnet, together with the natural period of vibration of the springs, supporting both the screen-carrying frame and the armature, all of which can be properly determined, built and adjusted when the apparatus is manufactured. Therefore no adjustment is necessary, since the load on the screen merely deflects the springs 13 and 14 without in any way changing the position of the armature or the relation between the armature and the frame.

In operation, the armature is resiliently pulled toward the magnet, all of the armatures being

simultaneously operated in the same direction, that is, in the apparatus shown, downward. The armatures are pulled downward until the cooperative striking blocks 33 and 34 engage when the screen is given a sharp jar and the armature is then immediately returned to its original position by means of the compressed lower springs of the pair of springs 32, when the cycle is repeated. The armatures can be provided with weights 35 when the machine is built, adjusted with respect to the other parts of the structure so as to give the best results and, since these weights are a permanent part of the electro-magnetic means, they cannot be tampered with in the field to modify the action for which the machine was first designed.

We have found that very satisfactory screening results are secured in an apparatus embodying our invention in which the screen-carrying frame, plus the screens with the weight of approximately 1,450 pounds, was supported on springs interposed between that frame and the rigid frame where the combined resistance of the interposed springs was approximately 11,500 inch pounds. With such a natural vibration frequency for the suspension of the screen, and with a frequency of 30 cycles per second at which the armature operated, very good results were secured. In this same construction the natural frequency of the armature, by reason of the resilient support therefor, was approximately 42 cycles per second, which corresponds relatively closely to the natural frequency of the supporting springs for the frame of 45 cycles per second.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a screening apparatus, the combination of a base, a screen frame supported on said base, resilient means interposed between said frame and base, means associated with said resilient means to confine movement of said frame to a plane substantially at right angles to the base, a vibrating means comprising an electromagnet fixed to said frame and immovable relative thereto, and an armature floatingly supported by said frame, opposed resilient means engaging opposite sides of said armature for providing said floating support for the armature, said armature being movable in a direction at right angles to the plane of the screen, under the influence of said electromagnet, a stop carried by said armature, and a cooperating stop on the frame so positioned that movement of the armature due to said magnet causes engagement of the stops to abruptly arrest movement of the armature.

2. In a screening apparatus, the combination of a base, a screen frame supported on said base, resilient means mounting said frame on said base, said means including upper and lower resilient members between which is interposed a portion of the frame, and a stud on said base connecting the upper and lower portions of said members, means on said stud for varying the compression of the resilient means, a vibrating means comprising an electromagnet fixed to said frame and immovable relative thereto, and an armature floatingly supported by said frame, opposed resilient means engaging opposite sides of said

armature for providing said floating support for the armature, said armature being movable in a direction at right angles to the plane of the screen, under the influence of said electromagnet, 5 a stop carried by said armature, and a cooperating stop on the frame so positioned that move-

ment of the armature due to said magnet causes engagement of the stops to abruptly arrest movement of the armature.
